UNITED STATES PATENT OFFICE.

GEORGE W. HEILAND, OF NEW YORK, N. Y.

SMOKE-MACHINE.

SPECIFICATION forming part of Letters Patent No. 740,650, dated October 6, 1903.

Application filed May 19, 1903. Serial No. 157,825. (No model.)

To all whom it may concern:

Be it known that I, GEORGE W. HEILAND, a citizen of the United States, and a resident of New York, in the county of New York and 5 State of New York, have invented certain new and useful Improvements in Smoke-Machines, of which the following is a specification.

This invention relates to a device for generating smoke and forcing it into a system of 10 pipes for the purpose of detecting and locating any leaks in the same. Smoke being very penetrating will when forced into pipes under a small pressure issue from any opening, however small, and from this a leak in 15 the pipes can be easily located.

The device consists of an inclosing case, preferably of metal and rectangular in form. In the lower part of this case is a fire-box and in the upper part a reservoir containing water. Located in this reservoir and partially immersed in the water is a cap or cover, which may be made of copper to prevent its corrosion by the water and is preferably cylindrical in form and pivoted at its ends to allow of its being oscillated, as will be herein-after described. This cover is open on one side; but when in position and hung on its pivots this opening is closed by the water, thus forming a chamber for the smoke generated in the fire-box below. Connection-pipes, with suitable check-valves, are provided to allow the smoke to pass to this chamber from the fire-box. The smoke-chamber may be divided by a partition, as shown in 35 the illustration. This provides for a continuous flow of smoke from the machine as the cover is oscillated.

The operation of this machine is more fully explained hereinafter and shown in the accompanying drawings.

Figure 1 represents a general elevation of a device embodying my invention, showing the upper part cut away to better illustrate the cap or cover forming the smoke-chamber and the connecting-pipes with their valves. Fig. 2 represents an end elevation, in reduced scale, of the cap and upper part of the water-reservoir. Fig. 3 represents a side elevation of one end of same.

50 An inclosing case, which is preferably formed of metal, is shown at 1. In the lower part of this case is a fire-box provided with

a removable perforated grate 2. This fire-box is separated from the water-reservoir in the upper part of the case at the partition 3. 55 A cap or cover is shown at 4 in its preferred form, which is cylindrical, and divided through the center by a partition 5 and pivoted on a shaft 6. This cover is cut away at the under side, as shown in Figs. 2 and 3, and is immersed in the water contained in the reservoir deep enough to close this opening, thus forming two smoke-chambers in the inclosed space on either side of the partition 5. This cover is oscillated back and forth by means 60 of a handle 7, and as the water maintains a constant level, as shown at 8, the smoke-chambers are alternately increased and decreased in size, thus forming a suction to draw the smoke from the fire-box through the connecting-pipes 9, 10, and 11. The pipes 10 and 11 are provided at their upper ends with a flat hinged cap, such as 12, which forms a valve upwardly opening, which allows the smoke to pass out as the cover 4 is oscillated, but prevents its passing back on the return stroke. These caps are provided with a hooked hinge 70 to permit their removal for cleaning or adjusting, thus forming a valve of simple construction and improved form.

At 13 and 14 are shown outlet passages or pipes which are provided with check-valves, which may be of any approved form and which act oppositely to the corresponding valves at the upper end of pipes 10 and 11. 75 These outlet-pipes 13 and 14 are joined together at 15 by an ordinary T connection which is provided with a coupling-tail for connection to the pipes or drains to be tested.

The operation of the machine is as follows: 80 Having started a thick fire with greasy waste or other material in the fire-box, which will generate a dense smoke, the cover 4 is oscillated back and forth. On the upward stroke the smoke is drawn up by the suction through 95 the inlet-pipes 9 and 10 into the smoke-chamber and on the return stroke is forced through the outlet-pipes 14 and 15 to the exhaust connection. At the same time the reverse operation is taking place in the opposite smoke-chamber. It is thus seen that the smoke will issue in a continuous stream from the exhaust connection to the pipes being tested, which have previously been connected to the 100

exhaust connection 15 and have all other outlets closed.

The shaft 6, upon which the cover 4 is hinged, is held in a U-shaped support 16 at 5 its ends, which allows of its being easily removed and also will allow it to rise as the pressure increases in the pipes under test and so acts as a safety device to prevent the seals of the traps from being forced by too 10 great a pressure. As smoke is very penetrating, any leaks in the pipes can be easily detected and located. The cover remaining floating indicates that there are no leaks in the pipes. If the pipes leak, the cover will 15 slowly descend, and the speed with which it falls will indicate the extent of the leak.

It will be evident that many changes in detail of construction may be made in this device without departing from the scope of my 20 invention, and I do not confine myself to the exact construction shown, as it is intended as an illustration of a preferred form.

What I claim is—

1. A smoke-machine comprising in its construction an inclosing case, a fire-box, a water-reservoir, a smoke-chamber of variable 25 size, a passage connecting said smoke-chamber and said fire-box, means for varying the size of said smoke-chamber for the purpose 30 of drawing the smoke into and forcing the same out of the chamber and an outlet from said smoke-chamber to an exhaust connection.

2. The combination in a smoke-machine of 35 an inclosing case, a fire-box, a water-reservoir, a pair of smoke-chambers variable in size, passages connecting said smoke-chambers with said fire-box, means for varying the size of said smoke-chambers for the purpose 40 of drawing the smoke into and forcing the same out of the chambers and an outlet from said smoke-chambers to an exhaust connection.

3. In a smoke-machine, the combination of 45 an inclosing case, a fire-box, a reservoir containing water which closes one side of a smoke-chamber partly immersed therein, a smoke-chamber variable in size, means for varying the size of said smoke-chamber by immersing 50 the same in water for the purpose of drawing the smoke into and forcing the same out of

the chamber, a passage connecting said smoke-chamber and said fire-box, and an outlet from said smoke-chamber to an exhaust connection.

4. In a smoke-machine, the combination of an inclosing case, a fire-box, a reservoir containing water which closes one side of each of a pair of smoke-chambers partly immersed therein, a pair of smoke-chambers variable 60 in size, means for varying the size of said smoke-chambers by immersing the same in water, a passage connecting said smoke-chambers with said fire-box, and an outlet from said smoke-chambers to a common exhaust 65 connection.

5. In a smoke-machine, the combination of an inclosing case, a fire-box, a reservoir containing water which closes one side of each of a pair of smoke-chambers partly immersed 70 therein, a pair of oscillating smoke-chambers, variable in size, a reciprocating cover coacting with the water to vary the size of said smoke-chambers, passages connecting said smoke-chambers with said fire-box, and an 75 outlet from said smoke-chambers to a common exhaust connection.

6. In a smoke-machine, the combination of a metallic inclosing case, a fire-box located in the lower part of said case, a removable perforated grate forming the bottom of the fire-box, a water-reservoir located above said fire-box and forming the upper portion of the inclosing case, an inclosing cap immersed in the water and forming a smoke-chamber, a 85 passage connecting said smoke-chamber and fire-box, and an outlet from said smoke-chamber to an exhaust connection.

7. In a smoke-machine, the combination of a fire-box, a smoke-chamber, a smoke-pipe 90 connecting said smoke-chamber and said fire-box, an upwardly-opening cap at one end of said pipe removably pivoted at one side by means of a hooked hinge and forming a check-valve for said smoke-pipe.

Signed at New York, in the county of New York and State of New York, this 15th day of May, A. D. 1903.

GEORGE W. HEILAND.
